UNITED STATES PATENT OFFICE.

EDWARD L. LEIMBERGER AND ALBERT BRASHER, OF CHICAGO, ILLINOIS.

FEEDING ATTACHMENT FOR POWER WRINGERS.

Application filed July 21, 1921. Serial No. 486,486.

To all whom it may concern:

Be it known that we, EDWARD L. LEIMBERGER and ALBERT BRASHER, citizens of the United States, residing at Chicago, in the county of Cook and State of Illinois, have invented certain new and useful Improvements in Feeding Attachments for Power Wringers; and we do hereby declare the following to be a full, clear, and exact description of the invention, such as will enable others skilled in the art to which it appertains to make and use the same.

The invention has relation to certain new and useful improvements in a wringer and has for its primary object the provision of a device of the character stated which will be of such construction and operation as to reduce to the minimum the liability of the operator's hands being caught or injured by the pressure rollers.

The invention has for another object the provision of a wringer of the character stated in which auxiliary feed rollers will be employed in connection with a movable endless belt which passes also between the pressure rollers and cooperates therewith in wringing or pressing the washing fluid out of the clothes or articles passing between the pressure rollers.

The invention has for a further object the provision of a wringer of the character stated in which the auxiliary feed rollers will be adapted for cooperation with portions of the endless movable belt at points between the outer guide rollers or idlers for the belt, and the pressure rollers, so that the belt will give and thereby eliminate danger of the pressure rollers crushing the hands of the operator while guiding the articles beneath the feed rollers to pass to the pressure rollers.

The invention has for a further object the provision of a wringer of the character stated in which the feed rollers will be resiliently forced toward the guide or feed belt without exerting enough pressure on the belt to cause a catching or pressing of the hands of the operator.

The invention has for a still further object the provision of a wringer of the character stated in which the belt will be mounted in a special manner with reference to the pressure rollers and the feed rollers on either side of and spaced from the pressure rollers, so as to properly guide the articles beneath either of the feed rollers and between the pressure rollers.

The invention has for a still further object the provision of a wringer of the character stated in which the feed rollers will be mounted in a special manner and connected so that when one of the feed rollers is in operative position, the other feed roller will be automatically raised and held in elevated position to prevent interference with the discharge of the pressed articles from the wringer.

The invention has for a still further object the provision of a wringer of the character stated in which the guide or feed belt may travel above and at a spaced distance with reference to the drain board usually provided for such devices.

The invention has for a still further object the provision of a wringer of the character stated in which all of the rollers and the belt will be mounted in a special manner for the highest efficiency and cooperation with one another.

The invention has for still another object the provision of a wringer of the character stated in which the feed rollers may be locked in the desired position so that either feed roller may operate with the feed belt while the other roller is retained in elevated or inoperative position, the positions of the feed rollers being readily interchangeable so that the articles may be passed in either direction through the wringer.

The invention has for a still further object the provision of a wringer of the character stated which may be composed of the minimum number of parts of simple formation and in which the parts may be readily assembled, secured together and the feed rollers mounted in bearings including pressure springs with tension regulating means provided therefor and the bearings movable in guide slots provided therefor in the supporting arms for the end guide rollers or idlers provided for the feed belts.

The invention has for a still further object the provision of a wringer of the character stated in which the supporting means for the end guide rollers or idlers of the feed belt and the feed rollers and mounting means therefor may be carried on the central post which may be mounted on the edge of the washer or on any other supporting device, as desired.

With the foregoing and other objects in view as will appear as the description proceeds, the invention consists in the novel

construction, combination and arrangement of cooperating elements as hereinafter more specifically set forth, claimed and shown in the accompanying drawings forming a part 5 of the present application and in which:—

Figure 1 is an end elevation of the complete device.

Figure 2 is a side elevation thereof.

10 Figure 3 is a top plan view of the complete device.

Figure 4 is a vertical section on the plane of line 4—4 of Figure 3, looking in the direction indicated by the arrows.

15 Figure 5 is a section on the plane of line 5—5 of Figure 1, looking in the direction indicated by the arrows.

Figure 6 is a section on the plane of line 6—6 of Figure 3, looking in the direction indicated by the arrows.

20 Figure 7 is a vertical section on the plane of line 7—7 of Figure 3, looking in the direction indicated by the arrows.

Figure 8 is a transverse section on the plane of line 8—8 of Figure 7 looking in the 25 direction indicated by the arrows.

Figure 9 is a detail view through the locking means for the feed rollers.

Figure 10 is a horizontal section on the plane of line 10—10 of Figure 4, looking in 30 the direction indicated by the arrows.

Figure 11 is a detail view of one of the pressure rollers and the mounting means therefor, removed.

Referring more in detail to the drawings 35 in which similar reference characters designate corresponding parts through the several views, 10 indicates the central posts which are arranged in pairs and spaced from one another. The posts of each pair are also 40 spaced apart and have plates 11 positioned therebetween and extended vertically. These plates 11 serve as the bearing plates or bearing carrying plates within which the bearings 12 for the upper and lower pressure 45 rollers 13 are mounted. These rollers 13 have reduced spindles 14 formed on their opposite ends and projecting into the bearings 12. Suitable springs 15 are provided 50 between the posts 10 of each pair of central posts, to resiliently force the bearings 12 toward one another in order that the pressure 55 rollers 13 may be resiliently forced together to serve the purpose for which they are intended, as will be readily understood by parties familiar with this art.

Secured upon the outer face of the opposite or corresponding posts 10 of each pair, is a transversely extended rectangular frame 16, as will be readily understood by referring 60 to the drawings. A bracket 17 extends outwardly from each end of each of the frames 16, to thereby provide a pair of brackets for each pair of posts 10 and rotatably mounted in the extreme outer ends of the pairs of 65 brackets 17, are the extremities of spindles

18 (see Figure 1) of the outer end guide rollers or idlers 19 for the endless movable feed belt 20. Guide rollers or idlers 19 are of less diameter than the pressure rollers 13. The rolls 19 are so positioned that the 70 upper run of the belt 20 may be in a substantially horizontal plane and only raised slightly in its transverse central portion, at which point it passes between the pressure rollers and bears upon the upper face of 75 the lower pressure roller, as shown clearly in Figure 4 of the drawings. This belt 20 may move in either direction, as may be desired, during operation of the device. A drain board 21 is provided beneath one end of the 80 belt 20 in any suitable manner. Said drain board 21 may be formed as a part of the frame 16 or may be rigidly connected with the post 10, as desired. It will be understood that the drain board 21 is preferably 85 spaced beneath the lower run of the belt 20 a suitable distance, so as not to interfere with the operation of the belt 20. The brackets 17 have vertical guard plates 22 at their inner ends and projecting inwardly 90 therefrom to turn the articles away from the ends of the upper pressure roller 13 and thereby reduce to the minimum the liability of the articles becoming caught between the ends of the pressure roller 13 and the frame. 95 These guard plates 22 may be extended slightly toward the upper roller 13, as shown.

Each bracket 17 has a vertical pocket 23 formed in its main portion and opening at the upper edge thereof. These guide pockets 100 23 have central guide grooves 24, the purpose of which will presently appear. The grooves 24 are on the vertical walls of the pockets 23, as will be readily understood by referring to the drawings. (Figure 10.) 105

For cooperation with the feeding belt 20, feeding the articles to the pressure rollers 13, we have provided a pair of feed rollers 25, which although shown as being longitudinally corrugated are not necessarily so constructed and which are spaced outwardly from or in front of the pressure rollers 13, said feed rollers 25 being arranged so that while one roller 25 is raised, the other roller may be resting upon the upper run of the 110 belt 20 for cooperation therewith. The feed rollers 25 have reduced spindles or hub portions 26 at their opposite ends mounted in suitable bearings in blocks 27 which are in turn fitted movably in the vertically movable 115 carrier frames 28. The bearing blocks 27 are vertically movable in the carrier frames 28, as clearly shown in the drawings, particularly Figures 6, 7 and 8 and the springs 29 are provided for yieldingly forcing them 120 with the feed rollers 25 toward the lower ends of the carriers 28. Suitable tensioning or regulating screws 30 are threaded in the upper ends of the carriers 28 to regulate the tension of the springs 29. The carriers 125 130

28 are movable in the pockets 23 guided by the grooves 24, and the carriers at opposite sides of the frame are connected in pairs by a transverse bar 31 which extends above and 5 parallel with the roller 25. A connecting rocker arm 32 is provided for connecting the corresponding carrier frames 28 of each pair at the same side of the machine and the rock arms are pivotally mounted at intermediate points on the upper ends of the 10 plates 11, as shown at 33. It will be seen by referring to the drawings, particularly Figure 2, that when one pair of carriers 28 in its lowermost position to permit the feed 15 roller 25 to yieldingly rest on the feed belt 20 and cooperate therewith, the other pair of carriers 28 is in its raised position to elevate the feed roller 25 carried thereby. It will also be seen by referring to the drawings 20 that a pair of upstanding guard plates 34 is provided to prevent the articles from passing under the ends of the feed rollers 25. The guard plates 34 are arranged at the 25 inner faces of the brackets 17 adjacent the outer sides of the pockets 23 and are preferably extended slightly toward the rollers 25 for which they are provided.

As herein above indicated the feed rollers are adapted to receive rotary motion from 30 the feed belt which is preferably provided with an adhesive surface such as of rubber or the like, similar to that provided for the pressure rollers, and free to rotate in either direction of movement of the upper run of 35 the feed belt which is designed to receive motion from the pressure rollers which may be driven by any suitable power derived from any convenient source but not illustrated otherwise than that the spindles of 40 the pressure rollers are extended beyond the frame and broken away as indicated in Figures 2, 3 and 5.

It will further be noted that the feed rollers are adapted for alternate use and bear 45 upon unsupported intermediate portions of the feed belt between the terminal supporting rolls of the belt and the pressure rollers which constitute the driving element of the apparatus, each feed roller being designed 50 for use in advance of the pressure rollers or in contact with the advance portion of the feed belt which is moving toward the pressure rollers, and owing to the unsupported characteristic of the belt at the point 55 where the feed rollers come in contact therewith, the hand of an operator passing inadvertently between the feed roller and the belt in placing an article on the belt is not subject to crushing or any injury, by reason 60 of the fact that the belt is adapted to yield downwardly or in a direction perpendicular to its plane as will be obvious by reference to the drawings and particularly Figure 4 thereof.

Moreover, as above indicated, the opposite

feed rollers are yieldingly held in contact with the surface of the feed belt by means of the springs 29 which are adapted to be tensioned by means of the adjusting screws 30, but the carrier which supports the feed 70 roller which is arranged in operative position should be locked in its depressed position, and for this purpose we employ a locking means generally designated at 35 and consisting of latches 36 of which tapered 75 heads 37 are adapted for engagement with sockets or notches 38 in the carriers and are yieldingly held in engaging relation with said sockets by springs 39 coiled as illustrated upon the stub spindles 40 upon which 80 the arms or shanks of the latches are mounted. Latches 36 have grips or handles 41 projecting outward through slots 42 in brackets 17, and preferably the opposite latches, 85 which are designed to secure the complementary carrier blocks supporting each feed roller, are connected by a transverse brace rod 43 to insure cooperative action of the opposite latch members and enable the operator to actuate both latches from one side 90 of the machine.

It will further be noted that the lower run of the feed belt bears against the under side of the lower pressure roller 13 and that suitable tensioning means are provided for 95 the supporting rollers 19 of the feed belt, said tensioning means in the construction illustrated consisting of adjusting bolts 44 threaded in suitable guides 45 which receives the extremities of the spindles 18 100 which carry the guide rollers 19. (See Figure 4).

It will further be observed that where as in certain of the principal features the apparatus herein disclosed follows the lines 105 of the conventional or typical forms of power wringers it includes a rearrangement of the features which serves to increase the efficiency and reduce the risk of operation to the attendant, so that time may be saved 110 in the use of the same and the quality of the work performed may be improved.

What is claimed is:—

1. A wringer comprising supporting posts, frames mounted on said supporting posts, pressure rollers mounted in said supporting posts, arms extended from said frames in pairs, guide rollers mounted in said arms, a feed belt extended around said guide rollers and passing said pressure rollers to cooperate therewith, feed rollers mounted above said feed belt, means connecting said feed rollers to retain one of the said rollers in operative position with relation to said belt and the remaining feed roller in 120 inoperative position, and locking means for said feed rollers.

2. A wringer comprising pairs of main supporting members, pressure rollers extended between said pairs of main support- 130

- ing members, mounting means for said pressure rollers, arms extended from said main supporting members in pairs, guide rollers mounted in said pairs of arms, a feed belt 5 extended around the guide rollers and passing between said pressure rollers to feed articles to the same and carry articles away from said pressure rollers, feed rollers mounted for cooperation with said feed belt, 10 supporting and mounting members for the feed rollers connecting means for said last mentioned members, means for connecting the supporting and mounting means for said feed rollers to elevate one feed roller while 15 the other feed roller is in its lower operative position, and means for locking said feed rollers in set position.
3. A wringer comprising main supporting members, pressure rollers mounted in 20 said main supporting members, bearing arms extended from said main supporting members in pairs, mounting means for said bearing arms, guard members for the ends of said pressure rollers carried by said sup- 25 porting arms, a feed belt mounted for movement between said pressure rollers and co-operating therewith, supporting means for said feed belt carried by said arms, feed rollers above said feed belt and parallel with 30 said pressure rollers, mounting means for said feed rollers movable vertically in said arms to raise and lower said feed rollers, pressure regulating means for said feed rollers, guards for the ends of said feed roll- 35 ers carried by said arms, means connecting said mounting means for the feed rollers to retain one feed roller in elevated position when the remaining feed roller is in lowered operative position, and means for locking 40 said feed rollers in set position.
4. A wringer comprising main supporting members, pressure rollers mounted in 45 said main supporting members, tension regulating means for said pressure rollers, a feed belt movable between said pressure rollers, mounting means for said belt ex- tending in opposite directions from said

main supporting members, means for attaching said mounting means to said main supporting members, a pair of corrugated 50 feed rollers adapted to be adjusted vertically above the feed belt to cooperate therewith in feeding articles to said pressure rollers, means for retaining one of said feed rollers in operative position while the remaining 55 feed roller is elevated to inoperative position, tension regulating means for said feed rollers, and means for locking said feed rollers in set position.

5. A wringer having, in combination with 60 the pressure rollers, a feed belt for movement toward the meeting line of the pressure rollers and a feed roller in advance of the pressure rollers and bearing upon an intermediate portion of the feed belt, carrier 65 frames arranged at opposite sides of the feed belt for movement relatively thereto, spring actuated bearing blocks mounted in said carrier frames for supporting the feed roller, and means for locking the carrier 70 frames in their operative position.

6. A wringer having, in combination with the pressure rollers, a feed belt for movement toward the meeting line of the pressure rollers and a feed roller in advance of 75 the pressure rollers and bearing upon an intermediate portion of the feed belt, carrier frames arranged at opposite sides of the feed belt for movement in a plane perpendicular thereto, spring actuated bearing 80 blocks mounted in said carrier frames for supporting the feed roller, and means for locking the carrier frames in their operative positions, and consisting of pivotal 85 spring actuated latches, transversely connected for simultaneous operation.

In testimony whereof we affix our signatures in presence of two witnesses.

EDWARD L. LEIMBERGER.
ALBERT BRASHER.
